(57) **CLAIM**

The ornamental design for an eyeglass device for shower as shown and described.

DESCRIPTION

FIG. 1 is a front isometric view of an eyeglass device for shower;

FIG. 2 is a rear isometric view of the eyeglass device for shower of FIG. 1;

FIG. 3 is a front view of the eyeglass device for shower of FIG. 1;

FIG. 4 is a rear view of the eyeglass device for shower of FIG. 1;

FIG. 5 is a top view of the eyeglass device for shower of FIG. 1;

FIG. 6 is a bottom view of the eyeglass device for shower of FIG. 1;

FIG. 7 is a left side view of the eyeglass device for shower of FIG. 1; and,

FIG. 8 is a right side view of the eyeglass device for shower of FIG. 1.

The broken lines illustrate portions of the eyeglass device for shower that form no part of the claimed design. FIGS. 1-6 are shown with symbolic break lines on one side of the eyeglass device for shower. Any portion of the article between the symbolic break lines forms no part of the claimed design.

1 Claim, 4 Drawing Sheets
